Application December 8, 1943, Serial No. 513,371

7 Claims. (Cl. 250—20)

1

My invention relates generally to improved locked-in oscillator circuits, and more particularly to novel methods of, and means for, extending the lock-in range of frequency dividers of the locked-in oscillator type.

In his application Serial No. 430,588, filed February 12, 1942, patented August 22, 1944 as U. S. Patent No. 2,356,201, George L. Beers has disclosed and claimed novel circuits for receiving angle-modulated carrier waves employing a locked-in oscillator system acting as a frequency divider.

The locked-in oscillator operation may be explained on the following basis it being understood, of course, that the following explanation is my personal explanation: The angle modulated wave, of a predetermined mean or center frequency F , is applied to the input control grid of a tube of the pentagrid type. The output, or plate, electrode circuit is tuned to a desired sub-harmonic F/n , where n is a small whole number. In the illustrative embodiment described in the Beers patent the fifth subharmonic is developed across the plate circuit. The third grid of the pentagrid tube is regeneratively coupled to the plate circuit with the result that oscillations of mean frequency F/n are produced in the plate circuit. These oscillations occur even in the absence of signal voltage on the first grid. Suppose, now, that $F=4300$ kilocycles (kc.) per second, and a signal of that mean frequency is applied to the first grid. Assume, further, that the plate circuit is tuned to 860 kc. In other words, $n=5$ and the oscillator section operates to provide subharmonic oscillations of 860 kc. The grid voltage-plate current characteristic of the pentagrid tube is nonlinear; this would be true of any other type of tube. Hence, harmonics of F/n are impressed on the oscillator grid. These harmonics which are present on the No. 3 grid include the fourth $(n-1)F/n$ (3440 kc.) and sixth $(n+1)F/n$ (5160 kc.) harmonics of the oscillator current.

Hence, the signals of 4300 kc. will beat with these fourth and sixth harmonics $(n\pm 1)F/n$ to provide a difference frequency the same as the desired fundamental frequency of 860 kc. (the fifth subharmonic of 4300 kc.). Now, this new component (which I will term the "harmonic difference component" to distinguish it from the normal oscillator current) will not, in general, have the same phase as the normal oscillator current. It, thus, is equivalent to injecting into the plate circuit an out-of-phase current. This causes the tube to act in the manner of the well-known reactance tube. If the oscillator fre-

quency is not exactly one-fifth of the incoming signal frequency, the natural frequency of the plate circuit is pulled over until the oscillator frequency is exactly one-fifth. This causes the oscillator section to "lock in" with the applied signals.

The maximum amount the natural frequency of the oscillator can be pulled over, and still be "locked-in," occurs when the harmonic difference current is 90 degrees out of phase with respect to the normal oscillator current, since this gives the maximum out-of-phase current. When the injected (harmonic difference) current is leading the normal oscillator current, the oscillator section frequency will be pulled to one side of its natural frequency (860 kc.), and when the injected current is lagging, the oscillator frequency will be pulled to the other side of its natural frequency. It will be recognized that there will thus be developed in the plate circuit a frequency modulated current "locked-in" with the applied signals.

There is a limitation on the lock-in range. This arises from the fact that the amplitude of the fourth and/or sixth harmonic on the oscillator third grid is normally quite small. Accordingly, the amplitude of the injected current is also small, and thus it follows that the lock-in range of the oscillator section is limited. The result is that when the deviation of the oscillator frequency exceeds approximately 20 kc., from the oscillator mean frequency (860 kc.), the oscillator suddenly "breaks out" and its frequency returns to the mean frequency value. When the oscillator is used with a frequency discriminator in a frequency modulation receiver, distortion results by virtue of this phenomenon. There are practical operating causes for the "break out" of the locked-in oscillator.

If the receiver is mistuned slightly, as is readily done in the case of frequency modulation receivers, the "break out" of the locked-in oscillator will occur on one end of the frequency swing, even for normal 75 kc. swings or deviations. If the frequency modulation ("FM" hereinafter for brevity) transmitter over-modulates, the "break out" may occur on both ends of the swing. Likewise gradual drifts in frequency of the oscillator or discriminator can occur due to temperature or other changes during operation, thus causing mistuning and consequent "break out."

It may, accordingly, be stated that it is one of the important objects of my invention to provide a general method of extending the lock-in range of a locked-in oscillator thereby to overcome the

undesirable effects due to "break out" of the oscillator caused by insufficient harmonic on the oscillator grid.

Another important object of this invention is to provide a method of adjusting the range of a locked-in oscillator by control of the harmonic content of the voltage on the oscillator grid or the input grid.

Another important object of my invention is to provide a highly practical method of increasing the lock-in range of a locked-in oscillator of the type shown in the aforesaid Beers patent; the method comprising tuning the oscillator plate circuit sufficiently to one side of F/n so that it will readily lock in on one end of the frequency swing, and tuning the oscillator grid circuit sufficiently on the other side of the desired harmonic [$(n-1)F/n$ or $(n+1)F/n$] to help lock in the oscillator on the opposite end of the swing.

Another object of my invention resides in the provision of a frequency-dividing, locked-in oscillator having its tank circuit tuned to the desired subharmonic frequency of the input mean frequency, and also having an auxiliary circuit tuned to a predetermined harmonic of such subharmonic frequency for extending the lock-in range of the oscillator at the extreme frequency values of the input energy.

A more specific object of this invention is to improve the operation of an FM receiver of the type disclosed in the aforementioned Beers patent; the improvement residing in providing a frequency divider of the locked-in oscillator type, normally operating the oscillator at a frequency different from the predetermined center frequency of the following discriminator, when there is no incoming signal, and utilizing the resulting rectified output voltage for maintaining a tuning indicator in a no-signal indication state.

Still other objects of my invention are to improve generally the efficiency, reliability and range of locked-in oscillators, and more especially to provide locked-in oscillators of extended range which are economical in construction and assembly.

Other features and objects of my invention will best be understood by reference to the following description, taken in connection with the drawing, in which I have indicated diagrammatically several circuit organizations whereby my invention may be carried into effect.

In the drawings:

Fig. 1 shows one embodiment of my invention.
Figs. 2 and 4 are vectorial analyses of my improved circuit.

Fig. 3 shows the effect of the injected current on the tuned circuit.

Fig. 5 graphically illustrates an advantage of the system.

Fig. 6 shows a modification.

Figs. 7a and 7b show the response curves of the tuned circuits of Fig. 6.

Fig. 8 is a circuit diagram of an FM receiver to which a further modification of the locked-in oscillator is applied.

Figs. 9a and 9b show the response curves of the tuned circuits of the locked-in oscillator of Fig. 8.

Figs. 10, 11 and 12 show respectively the off-tune (or no-carrier), exact tune, and off-tune indications of the electronic indicator of Fig. 8.

Fig. 13 shows another embodiment of my invention.

Fig. 14 shows a method for amplifying the required harmonic.

Referring now to the accompanying drawings, wherein like reference numerals in the different figures designate similar circuit elements, reference is made to the circuit shown in Fig. 1 for an explanation of the fundamental mode of operation of my present invention. In Fig. 1 I have shown a locked-in oscillator which is of the general type shown in the aforesaid Beers patent. The circuit comprises a tube 1 which may be of the pentagrid type. Between the input grid 2 and the cathode 3 there is impressed high frequency energy of a predetermined frequency F . The plate 4 has connected in circuit therewith a resonant circuit 5 which is tuned to a subharmonic F/n of F , the symbol n denoting a small integer. By way of illustration, the fifth subharmonic may be employed. The plate 4 is, of course, established at a positive potential with respect to the grounded cathode. The second and fourth grids of the tube are connected in common to a source of positive potential, and these grids function as a positive screen grid for the intermediate grid 6.

The latter grid 6 is regeneratively coupled, as at 7, to the plate circuit 5. The fifth grid of tube 1 is connected back to the cathode, and the grid therefore functions as a suppressor grid. The cathode 3, grid 6 and plate 4 provide the oscillator section of the circuit. This oscillator section produces oscillations of the subharmonic frequency F/n . These oscillations are continuously produced even in the absence of input energy at grid 2. The oscillations developed across circuit 5 are transferred through the coupling condenser 12 to any utilization network.

As shown (neglecting for a moment resonant circuit 8, 11), the coil 7' has its lower end connected to ground through the resistor 9, and the latter is by-passed for high frequency currents by the condenser 10. This is substantially similar to the locked-in oscillator circuit shown in the aforesaid Beers patent. The current from the tube is not sinusoidal, but comes through as a series of pulses. These cause harmonics of the subharmonic frequency F/n to be developed in the plate circuit 5. These harmonics will be applied to the grid 6 because of the coupling 7. Furthermore, the grid 6 is operating with self-bias, and draws grid current during the positive swings of voltage. These pulses, also, contain the fourth harmonic of F/n .

Let us assume now that F has a value of 4300 kc. This frequency will beat with the fourth (3440 kc.) and/or sixth (5160 kc.) harmonics of the resonant frequency of the plate circuit thereby to provide the desired subharmonic of 860 kc. In this case it is assumed that the letter n is equal to 5. When the frequency of the incoming signal is exactly five times the natural frequency of the oscillator, the harmonic difference component will be in phase with the current in the oscillating plate circuit. The circuit becomes stable in this condition, and the injected current will lock in the incoming 4300 kc. signal with the 860 kc. current in the plate circuit. Since the injected current has the same phase and frequency as the normal current it is equivalent to an increased output from the tube.

Now assume for the moment that the incoming frequency is higher than 4300 kc. and is within the lock-in range, but that the oscillator has not yet locked in. The effect of the fourth harmonic will be to inject a current of slightly greater frequency than 860 kc. into the tank circuit. In Fig. 2, OA is a vector assumed to be rotating

860,000 times per second, and represents the normal current in the oscillator tank circuit. Let AB be a vector representing instantaneous injected current of frequency slightly greater than 860 kc. resulting from the fourth harmonic of the oscillator voltage beating with the incoming signal voltage. This vector will rotate slightly faster than 860,000 times per second, and thus will have an angular velocity relative to OA equal to the difference of the two angular velocities.

Now consider further the instantaneous condition shown in Fig. 2. The injected current AB has a component AC shown dotted in phase with OA and another component AD (shown dotted) 90° out of phase with respect to OA. The vector OB represents the resultant of OA and AB. Let this current OB be applied to a tuned circuit LC as shown in Fig. 3. Since the circuit LC is tuned to 860 kc., it will be at resonance with respect to the current OC, which is also 860 kc., and the total current C equals $i_a + i_b$. The quadrature current AD is a leading current at the instant shown, and the result is the same as though an additional condenser C' is in the circuit LC. The effect was to decrease the natural frequency of the tuned circuit LC by an amount proportional to the magnitude of the vector AD.

Now consider the condition at a later instant, as shown by Fig. 4, the incoming frequency being the same as in the preceding discussion of Fig. 2. The vector AB has rotated to the new position as shown. The injected current AB now has an in-phase component AC as before, but the component AD is now lagging instead of leading. If the current OB is now impressed on the circuit of Fig. 3, the lagging component AD will cancel part of the leading current through capacity C, and this will be equivalent to reducing the capacity C since it is now drawing a smaller leading current. This will raise the resonant frequency of the tuned circuit LC by an amount proportional to the magnitude of the vector AD.

It is now evident that the circuit of Fig. 1 behaves like a reactance tube circuit. It is easy to see that if the frequency of the incoming signal is approximately five times that of the tuned circuit 5, a point will be reached when the frequency of the tuned circuit becomes exactly one-fifth of the incoming signal frequency. When this happens the oscillator will "lock-in" with the incoming signal. This means that the amplitude and phase of the plate current now remain fixed with respect to the incoming signal.

If the incoming signal is exactly five times the frequency of the tuned plate circuit, the vector AB will be in phase with OA, there will be no lagging or leading component, and there will be no tendency to change the resonant frequency of tuned circuit 5. As the incoming signal frequency is decreased, the oscillator will remain locked in with it because the vector AB rotates to some position such as that shown in Fig. 2, thus decreasing the oscillator frequency. A further decrease in frequency will rotate the vector until it is 90° out of phase with respect to OA. Since this position gives the maximum amount of quadrature current it corresponds to the maximum amount that the oscillator frequency can be pulled over, and thus gives the lower limit of the lock-in range. If the incoming signal frequency becomes greater than five times the plate circuit frequency, the conditions will be similar except that the vector AB will be lagging, as shown by Fig. 4, instead of leading. The upper limit of the lock-in range is reached when the

injected current lags by 90°. The lagging current tends to reduce the effective capacity of the circuit, and thus raises the frequency.

The amount of fourth and/or sixth harmonic current which is applied to grid 6 is normally relatively small. This limits the lock-in range of the oscillator, since it limits the amount of the injected current. The result is that when the deviation of the incoming signal exceeds approximately 100 kc., the oscillator suddenly breaks out and the frequency goes back towards center. This will cause distortion. Reference is made to Fig. 5 wherein there is shown the "break-out" gap produced in the output from a frequency discriminator. The practical operating disadvantage of this "break-out" effect resides in the fact that if a receiver is mistuned slightly, the break-out will occur on one end of the frequency swing and even for normal 75 kc. swings. Such mistuning of a receiver is quite possible, since the average operator of a frequency modulation receiver finds it difficult to tune the receiver exactly. Again, if the FM transmitter station over-modulates, the break-out will occur on both ends of the frequency swing.

In accordance with my invention, the "break-out" effect is substantially eliminated by extending the lock-in range of the oscillator. This is very simply accomplished by increasing the amplitude of the harmonics on grid 6 at the ends of the lock-in range where they are needed most. One simple way of accomplishing this result is to insert in series with the grid coil 7' an auxiliary resonant network consisting of coil 8 and condenser 11 arranged in parallel. The parallel resonant circuit 8-11 is tuned to either the fourth or sixth harmonic of the subharmonic F/n , when $n=5$. Preferably, the fourth harmonic is employed. As a general proposition the auxiliary circuit 8-11 may be tuned to nearly any harmonic of the subharmonic frequency, and will give improved results. If circuit 8-11 is tuned to the second harmonic, the tube will actually distort this harmonic thereby yielding added fourth and sixth harmonics. When the circuit 8-11 is tuned to the third harmonic of F/n , then the result will be that the sixth harmonic will also be built up. Hence, it should be understood that the fourth harmonic is shown merely by way of illustration. By way of specific illustration the circuit 5 may have an inductive magnitude of 0.762 millihenry and a capacity of 45 micro-microfarads (mmf.). Coil 8 may have a value of 40.8 microhenries while condenser 11 can have a value of 52.5 mmf.

The effect of the auxiliary tuned circuit 8-11 is to increase the magnitude of the vector AB representing the injected current, as shown in Figs. 2 and 4. The resultant increase in the magnitude of the vector AD increases the lock-in range of the oscillator over the case where the auxiliary circuit 8-11 is omitted because the effect of this component on the resonant frequency of tuned circuit 5 is increased proportionately. The dotted crests of the curve in Fig. 5 show the effect of the auxiliary grid circuit 8-11 insofar as overcoming the "break-out" is concerned. When the oscillator frequency reaches the end of its range, instead of dropping back suddenly to center frequency, it shifts to another frequency ratio

$$\frac{46}{9}, \frac{41}{8}, \frac{44}{9}$$

etc. This has the effect on wide deviations of

producing the dotted substantially flat top crests shown in Fig. 5. This is a much less objectionable form of distortion. It is scarcely audible for deviations greater than 150 kc. The "break-out" effect will not occur until the applied energy at grid 2 is reduced to a small value by the selectivity of circuits which may precede grid 2.

It will be appreciated that by inserting into the circuit of grid 6, that is the oscillator section grid, a tuned circuit which is resonated to the fourth harmonic of the subharmonic F/n there is secured a very great increase in the magnitude of the fourth harmonic voltage. Of course, by increasing the "Q" of the auxiliary circuit 8-11, the fourth harmonic component on grid 6 may be still further increased. However, there exists the disadvantage that the sharpness of the auxiliary circuit may be increased to a point such that the fourth harmonic component will not be built up at the ends of the swing where it is most needed, whereas if the "Q" of the auxiliary circuit is made low enough to broaden out the circuit response, a reduction in output of the desired harmonic results.

I have found that this particular disadvantage may be effectively overcome in several ways. One of these ways is shown in Fig. 6. Here the single auxiliary circuit 8-11 is replaced by an overcoupled double-tuned circuit. The numerals 11 and 11' designate respectively the overcoupled double-tuned circuits, i. e. circuits whose coupling is tighter than critical coupling. The coupling transformer 12' of these overcoupled circuits has its constants chosen so that the response curve of the overcoupled circuits is indicated by the double-peaked curve P in Fig. 7a. It will be noted from the curve P that one of the peaks of the response curve occurs at a frequency less than the fourth harmonic frequency

$$\frac{4F}{n}$$

while the second peak occurs at a frequency greater than

$$\frac{4F}{n}$$

The oscillator section plate circuit 5 in that case has its natural frequency located midway between the spaced peak frequencies of the circuits 11 and 11'.

Fig. 7b shows the oscillator plate circuit resonant frequency in relation to the curve P of Fig. 7a. By this method the oscillator plate circuit is tuned to the mean or center frequency F/n , whereas the auxiliary network has its spaced peak frequencies located on respectively opposite sides of the desired fourth harmonic frequency. If desired, the overcoupled tuned circuits could be replaced by a plurality of tuned circuits whose constants are so related as to extend the lock-in range of the oscillator section.

In Fig. 8 I have shown still another method of extending the lock-in range of the oscillator section. The system shown in Fig. 8 includes the locked-in oscillator acting as a frequency dividing network in a receiving system of the type disclosed in the aforementioned Beers patent. As more fully explained in the Beers patent the locked-in oscillator functions concurrently to reduce or divide the mean frequency of the applied FM signal waves, and proportionately to reduce the extent of frequency deviation of the waves. Assuming that the FM receiver is of the superheterodyne type and that the networks prior to

the locked-in oscillator tube are conventional in nature, the transformer 13 will have its primary circuit 14 tuned to the operating intermediate frequency (I. F.) of the system.

As fully explained in the Beers patent, the received FM waves are those which are transmitted in the assigned FM band of 42-50 megacycles (mc). Of course, the invention is not limited to any particular frequency band or to the reception of FM waves, since it is generally applicable to angle modulated carrier waves. Those skilled in the art are fully aware of the fact that the FM waves transmitted in the aforementioned assigned FM band are now allotted a maximum over-all frequency swing of 150 kc. with respect to the mean or center frequency F_c . The extent of frequency deviation is dependent upon the amplitude of the modulation signals at the transmitter, while the rate of frequency deviation is dependent upon the modulation frequency per se.

The collected FM waves are selected in one or more stages of tunable radio frequency amplification, after which they are combined with locally-produced oscillations at the first detector network. The output of the first detector or converter is the I. F. (intermediate frequency) energy. In other words, the I. F. energy is the FM wave whose mean frequency has been reduced to a much lower frequency, but whose frequency deviation is unchanged. After amplification in one or more stages of I. F. amplifiers, the I. F. energy is applied to the locked-in oscillator for concurrent frequency division and frequency deviation reduction.

Above the I. F. transformer 13 I have depicted, in a purely graphic manner, the ideal response curve of the coupled primary and secondary tuned circuits 14 and 15. It will be seen that the mean frequency is located at 4.3 mc., whereas the pass band of the network is substantially 150 kc. wide. This signifies that the network 14-15 is capable of efficiently transmitting the entire frequency swings of the FM wave whose mean frequency has been reduced to the operating I. F. value. While the value of 4.3 mc. has been assigned as the operating I. F. value, it is to be clearly understood that any other satisfactory value may be employed depending upon the various factors met with in the design of the receiver.

Since the locked-in oscillator circuits in Fig. 8 are exactly the same as shown in Fig. 1, the same reference numerals are employed. The FM signal energy with its mean frequency at the operating I. F. value is applied to the input grid 2. The input grid 2 is connected to the high alternating potential side of the secondary circuit 15. The low potential side of circuit 15 is returned to the grounded cathode 3 through a resistor and condenser network designated by the numeral 16. The function of the network 16 is to provide voltage across the resistor element in response to grid current flow through the input grid circuit. Such grid voltage developed across the network 16 may be utilized for automatic volume control (AVC). The AVC voltage is employed automatically to bias the control grids of preceding amplifier tubes in a manner well-known to those skilled in the art.

The plate or primary circuit 5 in the embodiment of the invention shown in Fig. 8 is resonated to a frequency located to one side of the mean output frequency. For example, if the mean output frequency is to be 860 kc., assuming a frequency division by a factor 5, then circuit 5 is tuned to a frequency greater than 860 kc. By way of spe-

cific example, the plate circuit frequency could be 875 kc. The auxiliary resonant circuit 8-11, which is arranged in circuit with grid 6 and the secondary or feedback coil 7', is tuned to a frequency less than the fourth harmonic of 860 kc. In other words, circuit 8-11 is tuned to less than 3440 kc. For example, the frequency could be 3380 kc. Of course, it could also be tuned to less than the sixth harmonic 5160 kc. were it desired to employ the sixth harmonic. As a specific example of constants for circuit 5, there may be employed an inductive value of 0.735 millihenry and a capacity value of 45 mmf. at the frequency of 875 kc. Coil 8 and condenser 11 could be 40.8 microhenries and 54.4 mmf. respectively at 3380 kc.

In Figs. 9a and 9b I have depicted in a purely qualitative manner the relation between the response or resonance curves of the oscillator plate circuit 5 and the auxiliary tuned circuit 8-11. It will be noted that the peak response of the plate circuit 5 occurs at greater than 860 kc., that is, the selected subharmonic frequency lies on the low frequency portion of the curve, while the resonant frequency of the auxiliary tuned circuit is less than 3440 kc., that is, the harmonic of the selected subharmonic lies on the high frequency portion of the curve. The important advantage of this off-tuning of the circuits 5 and 8-11 is that the oscillator section will lock in on one end of the frequency swing by virtue of the mistuning of circuit 5, while it will be locked in at the opposite end of the swing by virtue of the circuit 8-11. In other words, the lock-in range of the oscillator section will be extended at the extremes of the range.

Above the plate circuit 5 in Fig. 8 I have graphically represented the ideal response curve of the oscillator section output network. It will be noted that it has a pass band width of 30 kc., while the mean frequency has a value of 860 kc. This is appropriate since the effect of the locked-in oscillator network has been to divide the mean frequency of the FM wave energy by a factor of 5, and the over-all frequency deviation range has also been divided by the same factor. Additionally, there is secured a substantial reduction of amplitude modulation effects which may have been created on the FM wave energy in the transmission through space or during the passage of the signal energy through the receiver networks.

This elimination of amplitude modulation effects is secured, as explained in the aforesaid Beers patent, without the use of any special amplitude limiter stage. The advantages of frequency division at this point of the receiving system also have been explained in the Beers patent. The extension of the lock-in range of the oscillator accomplished by this invention as compared with the arrangements shown in the Beers patent will enable reception of waves which are frequency modulated over a wider range and will guard against the distortion which might otherwise occur by reason of the aforementioned "break-out" effect. Since the FM wave energy developed across the plate circuit 5 is modulated in strict accordance with the originally received FM waves, save that the mean frequency and extent of frequency deviation have been proportionately reduced, the output of the locked-in oscillator may now be subjected to any well-known form of discrimination and rectification.

The numeral 16 denotes a discriminator input circuit which feeds a pair of opposed diode rectifiers 17 and 18. The discriminator input circuit

16 is shown only in block diagram, because it is not part of the present invention so far as its specific construction is concerned. The type of discriminator input circuit shown in the Beers patent may be utilized. That type of discriminator input circuit is disclosed and claimed by J. D. Reid in application Serial No. 353,028, filed Aug. 17, 1940, U. S. Patent No. 2,341,240, granted February 8, 1944. In place of the Reid discriminator there may be employed the well-known form of discriminator shown by S. W. Seeley in his U. S. Patent No. 2,121,103, granted June 21, 1938. There may, also, be employed for the discriminator input circuit 16 the form wherein each rectifier has an input circuit individual to itself, and the input circuits are oppositely mistuned relative to the mean frequency of the applied signal energy as in the U. S. patent to Conrad, 2,057,640. In any event, and regardless of the construction of the discriminator input circuit 16, the opposed diodes 17 and 18 will be separately fed with signal energy which has the form of amplitude modulated wave energy by virtue of the action of the discriminator input circuit 16 which translates the FM wave energy into corresponding amplitude modulated carrier wave energy.

As will be noted from Fig. 8, the output load consists of a pair of series-connected resistors 19 and 20. The junction of the resistors is connected by a return path 21 to the discriminator section. Each of the load resistors 19 and 20 is bypassed for high frequency currents by means of suitable condensers, and the cathode of the diode 18 is established at ground potential. Above the discriminator-rectifier network I have shown a typical S-shaped response curve of an FM detector stage. It will be noted that at the mean frequency F_c the resultant output voltage of the detector is zero. The maximum output occurs at the opposite peak limiting frequencies F_1 and F_2 . Those skilled in the art of radio communication and FM transmission and reception are well-acquainted with the manner in which this device operates.

Each of the opposed rectifiers includes in circuit therewith its respective load resistor. At the instant when the applied signal energy has the mean frequency value, the rectified voltages across the resistors 19 and 20 are equal in magnitude and opposite in polarity. Hence, the resultant potential at the upper end of resistor 19 is zero. On the other hand the potential at the upper end of resistor 19 will vary in magnitude and polarity, depending upon the instantaneous extent and direction of frequency deviation with respect to the mean frequency. Accordingly, the voltage taken off from the output load of the opposed rectifiers corresponds to the original modulation signal voltage applied to the carrier at the FM transmitter.

Since the plate circuit 5 of the oscillator section of tube 1 in Fig. 8 is normally mistuned with respect to the mean frequency of 860 kc., advantage is taken of that fact to provide a novel, highly effective and simple form of resonance indication. In providing a resonance indicator for the receiving system shown in Fig. 8 there is utilized an indicator tube 22 of the well-known 6E5 type. Those skilled in the art are well acquainted with this type of indicator tube. The numeral 22 denotes the indicator tube. It comprises a pair of electronic sections. One of these sections is a triode consisting of a cathode electrode 23, a control grid 24 and a plate 25. The

cathode 23 is connected to ground by means of a resistor S which is adjustable in magnitude. The control grid 24 is connected to the ungrounded end of resistor 19 through a path which consists of resistor R and the filter resistor 28.

The grid 24 is connected to ground by a condenser C for bypassing audio frequency voltages. The resistor 28 and the pair of parallel condensers 29 provide a de-emphasis network whose function is well known in the art of frequency modulation reception. Briefly, the de-emphasis network acts to diminish the response at the higher audio frequencies, since during transmission of the FM waves such higher audio frequency components may have been disproportionately emphasized. It should be noted that the lead to resistor R can be connected to either side of resistor 28. It will, therefore, be seen that the control grid 24 of the triode section of the indicator tube is varied in potential in accordance with the magnitude and polarity of the voltage existing at the upper end of resistor 19. Since the condenser C filters out any audio frequency variations, it follows that the voltage of grid 24 will be a function of the variations in mean frequency of the FM wave energy applied to the discriminator input circuit 16.

The upper electronic section of tube 22 is the indicator section. It consists of a cathode section 23' which is actually an extension of the cathode electrode 23, except that the sections 23 and 23' are spaced by a non-emissive section. However, the sections 23' and 23 are at a common potential. The indication electrode has a configuration of an inverted frustum of a cone. The numeral 26 denotes the outwardly flaring electrode. The inner face of electrode 26 is coated with a fluorescent composition which will fluoresce upon the impingement of electrons emitted by the cathode section 23'. In other words, the electrode 26 functions as a fluorescent target.

The target electrode is connected to a source of +250 volts, and the triode plate 25 is connected to the same potential point through the resistor r. The numeral 27 designates an electron deflection rod or electrode which is directly connected to the plate 25. It will, therefore, be appreciated that the rod 27 follows the potential variations of plate 25. More specific details of the construction of an indicator tube of this type will be found disclosed and claimed by H. M. Wagner in his U. S. Patent No. 2,051,189, granted Aug. 18, 1936.

It is sufficient for the purposes of this application to explain that the magnitude of the cathode resistor S is adjusted so that grid 24 has a normal direct current voltage with respect to cathode 23 such that the electron shadow provided on the target 26 is of minimum width. Let it be assumed that no signal energy is being received. Under these conditions the indicator tube will function in the following manner: The normal voltage drop across the cathode resistor S gives the grid 24 a normal negative bias such as to provide a normal plate current flow through the resistor r. The deflection electrode 27 is biased by the voltage drop across the plate resistor r so as to provide a minimum deflection of electrons. Since, in the absence of signal energy, the plate circuit 5 of the oscillator tube 1 is tuned to a frequency greater than 860 kc., and since 860 kc. is the mean frequency of the FM detector characteristic, there will be developed a certain positive potential at the upper end of

resistor 19 which is applied to grid 24. This positive voltage renders the grid 24 less negative with respect to the cathode, and permits an increased space current flow through the plate resistor r. As a consequence, the rod 27 will become effectively more negative with respect to the target 26. This means that the electrons will not be curved around the rod, and will not strike the target area in front of rod 27. In other words, the shadow sector will widen.

In Fig. 10 I have shown the appearance of the shadow area 26' on the fluorescent face of target 26 when no signal energy is being received. Fig. 11 shows the minimum width of the shadow area 26' when the signal energy applied to the FM detector has a mean frequency of exactly 860 kc. It will be noted that the shadow area has been narrowed to a considerable extent, because the voltage at the upper end of resistor 19 is zero when the applied signal energy has a mean frequency at the discriminator input circuit which is equal to the center frequency of the FM detector characteristic. Hence, the deflection electrode 27 will be less negative with respect to the target 26, and the electrons will be curved around the rod to strike the target behind the rod and thus close the eye.

Fig. 12 shows the appearance of the target 26 when the signal energy applied to the discriminator input circuit has a mean frequency which is less than 860 kc. The result is a very bright overlap instead of an electron shadow. Fig. 10 also shows the appearance of the target when the signal energy applied to the discriminator has a mean frequency which is greater than 860 kc.

It will now be appreciated that I have provided a simple and effective resonance indicator which indicates by virtue of minimum shadow area that the receiver is exactly in tune. However, when the mean frequency of the applied signal energy drifts away from F_c toward F₂ (that is, in the direction of the normal frequency of plate circuit 5 of the locked-in oscillator), the shadow area 26' widens out to indicate that the receiver is mistuned to that side of exact tuning. On the other hand, when the mistuning occurs in the opposite direction, toward F₁, there appears an area of very bright overlap thereby instantly indicating that condition of mistuning. In the prior art, resonance indicators of the fluorescent target type used on standard FM receivers did not distinguish between absence of signal energy and mistuning. It will be seen that in accordance with my invention it is possible under some conditions to distinguish absence of signal energy from mistuning.

The methods of Figs. 1, 6 or 8 can also be used in the input grid circuit of tube 1. Fig. 13 shows one embodiment of my invention wherein the tuned circuit 8—11 is located in the circuit of grid 2. I have found that this also will build up the required harmonic on the grid 2 and increase the lock-in range.

The invention is not restricted to frequency modulated signals, but can also be used at any fixed frequency. The increased lock-in range is desirable when operating at a fixed frequency to assure that the oscillator will remain locked in even though the circuits may become slightly misaligned due to temperature changes, voltage changes, etc. The use of a locked-in oscillator with a frequency discriminator represents only one application. It can be used to obtain secondary frequency standards from a given primary standard such as a crystal oscillator; it

can be used to compare two frequencies; to operate electronic clocks; or in any other application where a definite ratio of frequencies is desired. It should be further noted that my invention is not limited to the use of a pentagrid-type tube. It will operate with any tube which is normally used as an oscillator.

Fig. 14 shows another embodiment of my invention. The capacitor 35 couples the tuned plate circuit 5 to the grid 38 of an amplifier tube 38' which is biased to give high distortion. Generally, any non-linear amplifier may be employed as a harmonic generator. The tuned circuit 39 is tuned to the desired harmonic that is to be impressed on the oscillator grid. This tuned circuit 39 is coupled as at 37 to the grid 6 of tube 1. This modification operates in the same manner as the circuit 8-11 of Fig. 1, except that the required harmonic is stronger than that obtained in Fig. 1. It can also be adjusted by varying the gain of tube 38, which although shown as a triode can be any other well known amplifier tube, such as a pentode. In like manner, the amplifier tube can also be used in combination with any of the other circuits described above to control and increase the harmonic content in the circuits.

While I have indicated and described several systems for carrying my invention into effect, it will be apparent to one skilled in the art that my invention is by no means limited to the particular organizations shown and described, but that many modifications may be made without departing from the scope of my invention.

What I claim is:

1. In combination with a tube provided with at least an electron emitter, a control element, an oscillator grid and oscillator output electrode, means for applying to the control element high frequency current which is angle modulated and has a desired mean frequency, a resonant tank circuit reactively coupled to said oscillator grid and output electrode and tuned substantially to a desired subharmonic frequency of said mean frequency for normally and continuously producing oscillatory current of said subharmonic frequency, means including a selective network tuned substantially to a harmonic of said subharmonic which differs from the mean frequency by the subharmonic frequency, means coupling said selective network to said tank circuit and oscillator grid, means for deriving from the angle modulated current of subharmonic frequency the modulation thereof, a tuning indicator, and means responsive to normal current of said tank circuit for maintaining the indicator in no-signal indication state.

2. In combination with a tube provided with at least an electron emitter, a control element, a grid and output electrode, means for applying to the control element frequency modulated carrier current of a desired frequency, a resonant tank circuit tuned to a subharmonic frequency of said desired frequency and including a first inductor connected to said output electrode and a second inductor connected to said grid electrode and coupled to said first inductor so as to produce continuously oscillations of said subharmonic frequency, a selective network auxiliary to said tank circuit and in circuit with the tank circuit and tuned to a harmonic of said subharmonic which differs from the carrier frequency by the subharmonic frequency, and additional means for applying harmonic current developed in said selective network to said oscillator grid.

3. In combination with a locked-in oscillator

tube provided with at least an electron emitter, a control element, an oscillator grid and oscillator output electrode, means for applying to the control element high frequency current which is angle modulated and has a desired mean frequency, means including a resonant tank circuit for generating continuous oscillations, said tank circuit reactively coupling said oscillator grid and output electrode and being tuned normally to a frequency which is greater than a desired subharmonic frequency of said mean frequency so that said subharmonic lies on the low frequency portion of the response curve of said tank circuit, a selective network tuned to a frequency which is less than a desired harmonic of said subharmonic so that said harmonic lies on the high frequency portion of the response curve of said network, which said harmonic differs from the mean frequency by the subharmonic frequency, said selective network being coupled to said tank circuit and to said oscillator grid, means for rectifying the current of subharmonic frequency in said tank circuit, a tuning indicator, and means responsive to rectified current in no-signal state for controlling the indicator.

4. In combination with a tube provided with at least an electron emitter, a control element, an oscillator grid and oscillator output electrode, means for applying to the control element frequency modulated high frequency current of a desired center frequency, a resonant tank circuit reactively coupling said oscillator grid and output electrode and tuned substantially to a desired subharmonic frequency of the said center frequency, a pair of coupled selective networks each tuned to a harmonic of the subharmonic frequency, and means connecting said selective networks to said oscillator grid thereby applying harmonic current developed in said selective networks to said oscillator grid.

5. In combination, in a frequency modulation receiver, a tube provided with at least an electron emitter, a control element, an oscillator grid and oscillator output electrode, means for applying to the control element frequency modulated current of a desired mean frequency, a resonant tank circuit reactively coupled to said oscillator grid and output electrode and tuned to a frequency which is greater than a desired subharmonic frequency of said mean frequency so that said subharmonic lies on the low frequency portion of the response curve of said tank circuit, a selective network tuned to a frequency which is less than a desired harmonic of said subharmonic so that said harmonic lies on the high frequency portion of the response curve of said network, which said harmonic differs from the mean frequency by the subharmonic frequency network to said tank circuit and oscillator grid said selective network being in series with said coupling means and said oscillator grid, and means for deriving from the frequency modulated current of said tank circuit the modulation thereof.

6. In combination with a locked-in oscillator tube provided with at least an electron emitter, a control element, an oscillator grid and oscillator output electrode, means for applying to the control element high frequency current which is angle modulated and has a desired mean frequency, a resonant tank circuit reactively coupling said oscillator grid and output electrode and tuned normally to a frequency which is greater than a desired subharmonic frequency of said mean frequency so that said subharmonic lies on the low frequency portion of the response curve

of said tank circuit, a resonant circuit tuned to a frequency which is less than a desired harmonic of said subharmonic so that said harmonic lies on the high frequency portion of the response curve of said resonant circuit, which said harmonic differs from the mean frequency by the subharmonic frequency, said selective network being auxiliary to said reactive coupling, and means coupling said selective network to said tank circuit and oscillator grid.

7. In combination with a locked-in frequency dividing, oscillator tube provided with at least an electron emitter, a control element, an oscillator grid and oscillator output electrode, means for applying to the control element frequency modulated current of a desired center frequency, a resonant tank circuit including primary and secondary windings regeneratively coupling said oscillator grid and output electrode, said primary winding being tuned to a frequency which is greater than a desired subharmonic frequency of said mean frequency so that said subharmonic lies on the low frequency portion of the response curve of said tank circuit, a resonant circuit tuned to a frequency which is less than a desired harmonic of said subharmonic so that said harmonic lies on the high frequency portion of the response

curve of said resonant circuit, which said harmonic differs from the mean frequency by the subharmonic frequency, said last resonant circuit being auxiliary to the regenerative coupling, said resonant circuit being in series with said secondary winding and said oscillator grid whereby harmonic current developed in said resonant circuit affects the electron stream.

MURLAN S. CORRINGTON.
